BRACE

Filed April 19, 1924

Inventor

Arnold Hanak

By Arnold F. Morris
Attorney

UNITED STATES PATENT OFFICE.

ARNOLD HANAK, OF VIENNA, AUSTRIA.

BRACE.

Application filed April 19, 1924. Serial No. 707,733.

To all whom it may concern:

Be it known that I, ARNOLD HANAK, a citizen of the Republic of Austria, residing at Vienna, Austria, have invented certain 5 new and useful Improvements in Braces (for which I filed an application for patent in Germany on February 10, 1923), of which the following is a specification.

This invention relates to improvements in 10 braces made of india rubber.

In the manufacture of braces either rubbered fabric has hitherto been used or rubber without interwoven fabric the straps being made with circular holes. Neither of 15 these articles, however, were fully satisfactory as regards elasticity and permeability of the warmth of the body; if rubbered fabric is used the elasticity is limited by the cotton threads; a further disadvantage consists in that the bearing straps becomes 20 warm by friction, and being of non-porous material will not allow the warmth and moisture of the body to be dissipated.

The latter inconvenience also occurs when 25 rubber braces without interwoven fabric are used owing to the fact, that the straps will fit tightly to the body thereby rendering the use of such braces very disagreeable particularly in summer or in countries having a hot 30 climate.

Moreover the manufacture of the said articles is not sufficiently simple and the costs are rather high.

This invention relates to braces or suspenders of high elasticity in which the above mentioned drawback of impermeability is

overcome by the provision of appropriately sized longitudinal slots in the shoulder strap portions narrow ribbons being formed therebetween, the walls of said slots functioning 40 to stretch and contract with the movements of the body in those portions of the suspenders which fit tightly against the body, causing an alternate puckering and stretching of the garment worn beneath the 45 shoulder strap portions, thereby inducing a change of air beneath the slots which contributes to the comfort of the suspenders.

The accompanying drawing shows an embodiment of the invention by way of example. 50

In the strap A which consists of india rubber slots B, B₁, B₂, B₃ and so on are punched narrow ribbons C, C₁, C₂, C₃ and so on being formed thereby. 55

Similar bearing straps may be used for suspending stockings and socks.

What I claim is:

An article of manufacture, a garment suspender including shoulder strap portions 60 made integrally of a single piece of india rubber having the entire length of the shoulder strap portions formed with longitudinal slots of appreciable width, forming between them relatively narrow spaced strips. 65

In testimony whereof I have hereunto set my hand.

ARNOLD HANAK.
